UNITED STATES PATENT OFFICE.

LLOYD BLACKMORE, OF HIGHLAND PARK, MICHIGAN, ASSIGNOR TO GENERAL MOTORS CORPORATION, OF DETROIT, MICHIGAN, A CORPORATION OF DELAWARE.

HORN BUTTON.

Application filed January 30, 1926. Serial No. 84,903.

My invention relates to switches and more particularly to switches adapted to be mounted on the top of steering wheel columns of motor vehicles for actuating a sound signal, such as a horn or bell.

One of the objects of my invention is to provide a switch of simple and inexpensive construction, free of rattle, readily assembled and positive of operation.

This invention consists of the novel arrangement, construction and combination of parts as hereinafter more particularly described in the following specification, and pointed out in the annexed claims. Other objects will appear hereinafter.

In the accompanying drawings:

Figure 1 is a fragmentary view of the top of a steering wheel column, having mounted thereon a switch, shown in section, constructed in accordance with the principles of my invention.

Figure 2 is an enlarged perspective view of the switch insulation base.

Figure 3 is an enlarged perspective view of the socket member for housing my improved switch.

Figure 4 is an enlarged perspective view of a button for the switch.

Figure 5 is an enlarged perspective view of a yoke for the switch.

Figure 6 is an enlarged perspective view of a spring for the switch.

My improved switch is particularly adapted to be used on tubular types of steering columns, and, in this instance, is mounted in a socket or tubular extension 7, carried on a steering column 8, above the steering wheel, as indicated in Figure 1.

The various parts assume, preferably, the construction as illustrated in Figures 2 to 6, inclusive, that is, the actuating member 10 comprises a button and a hollow shank 11, carried thereby. A base member 12 is constructed of insulation material shaped to fit inside the socket 7 and has formed on its upper and end surfaces suitable grooves 13 and 14 and recesses 16, 17 and 18, as indicated in Figure 2, for a purpose hereinafter to be seen. The said base, moreover, is constructed to carry a central contact member 19 for connection with a conducting wire 20 clamped thereto by a clamping screw 21. The upper surface of the base 12, around the said contact member, may conveniently 55 be formed with a shallow basin 12^a.

A flat spring 26 is constructed to lie across the basin 12^a in the said grooves 13, and is of a convenient length to be carried by a yoke 27. Said yoke 27 is formed with a central aperture 21^a provided with a short upturned flange 21^b to receive the shank 11 of the button 10, and carries depending tabs 28 and a side tab 29, said tabs serving to fasten together, in the manner illustrated in Figure 1, the various parts of the said switch. The socket, or tubular extension 7 is formed with a suitable aperture 30 to receive a clamping screw 31 for engagement with a threaded aperture 32 in the side of the said yoke.

In the assemblage of my device, the yoke 27 is mounted on the shank of the button 11, and is secured thereto by spinning over the bottom marginal portion of the stem 11^a, as indicated in Figure 1. The spring 26 is then placed between the two arms of the yoke and locked therein by turning in the said side tab 29.

It will be noted, as indicated in Figure 1, that the shank 11 extends slightly beyond the aperture 21^a in the yoke 27, whereby the spring 26 is caused to assume a slightly curved position. By such a construction, it will be evident that the stem 19 will be constantly urged upwardly; and, in such a manner as to contact with the said yoke, thereby resiliently holding the button in its raised position. The yoke 27, carrying the spring and button, is then fitted over the base 12 and disposed in the said grooves 13 and 14, formed thereon to receive the said spring and the arms of the said yoke, the inwardly extending tab 29 being received by the said recess 17. The yoke is then secured to the base 12 by bending the tabs 28 into the aforesaid recesses 16. A wire 20, housed within the steering column and connected with a horn and battery (not shown) is then clamped to the said contact member 19 by the screw 21. The parts, thus secured, are disposed within the socket 7 and secured therein by the said screw 31, positioned in the aperture 30 and engaging the said threaded aperture 32 in the side of the yoke 27, the aforesaid recess 18 conveniently receiving the extended end of the said set screw.

In operation, the actuating member 10 is pressed down against the resistance of the spring 26 and brought into electrical con-

tact with the contact member 19. Electrical contact having been made, it will be obvious that the horn (not shown) will then be grounded through the spring 26, the yoke 27, the set screw 31 seated in the socket 7, and the various metallic parts of the steering column. It will be obvious that by reason of the short upturning flange 21^b surrounding the aperture 21^a of the yoke 27, a degree of lateral movement of the button stem will be permitted.

From the foregoing it will be seen that I have provided a construction, arrangement and disposition of various parts which will 15 allow a complete freedom of play of the actuating member with respect thereto without sacrificing the structure to any undesirable rattling, and yet always obtain a positive point of contact, and a device which 20 fully attains the objects hereinbefore set forth.

Modification of the above may be made within the spirit and scope of my invention.

I claim:

- 25 1. In a switch, a base of insulating material having a central contact member, a flat spring extending across the top of said base, a bridge piece over said spring and secured to said base and having an orifice there-
30 through and a headed button having a shank extending through the orifice in said bridge piece and spread to form a retaining head between said bridge piece and said spring.
- 35 2. A switch comprising a base of insulation material, a stationary contact member, a strap fastened across the said base and provided with a central aperture, an actuating member comprising a button and a
40 headed shank fitted in the said aperture, a movable contact member locked in the said strap and so positioned as to maintain a retractile engagement of the said headed shank with the said strap.
- 45 3. A switch including a base of insulation material, a stationary contact member secured in said base, a strap fastened across the said base and formed with a central aperture, an actuating member comprising
50 a button and a headed shank fitted in the said aperture, a movable contact member locked into the said strap, and so positioned as to maintain a retractile engagement of the said headed shank with the said strap.
- 55 4. In a switch, the combination of a housing, a supporting yoke, an insulation member formed to receive the said yoke, a conducting element carried in the said insulation member, and means to ground the said
60 conducting means, comprising a tilttable actuating member and a metallic strip, both being mounted in the said yoke.
5. In a switch, the combination of a housing, a supporting yoke, an insulation mem-
65 ber formed to receive the said yoke, a con-

ducting element carried in the said insulation member, a flat spring disposed in spaced relation from the conducting element and locked into the said yoke, and an actuating means carried in the said yoke and positioned to slightly depress the said spring, the latter being maintained in spaced relation with respect to the said conducting member, whereby the said actuating member normally assumes a fixed position, and is yieldable only to operating pushes. 70 75

6. In a switch, the combination of a housing, a supporting yoke, an insulation member formed to receive the said yoke, a conducting element carried in the said insulation member, a flat spring associated with the said yoke being normally retained in spaced relation from the said conducting member by the resiliency of the said spring, and means mounted in the said yoke to actuate the said spring. 80 85

7. In a switch, the combination of a housing, a supporting yoke, an insulation member formed to receive the said yoke, a conducting element carried in the said insulation member, a flat spring disposed in spaced relation from the said conducting member and locked into the said yoke, and means maintained in retractile position by the said spring extending through the said yoke for actuating the said spring and producing an electrical contact between the said spring and the said conducting member. 90 95

8. In a switch, the combination of a housing, a supporting yoke, an insulation member formed to receive the said yoke, a conducting element carried in the said insulation member, a flat spring disposed in spaced relation from the conducting element and locked into the said yoke, and an actuating means urged upward out of operative position by the said spring, and means extending through the said yoke so mounted as to transmit positively to the said spring a pressure imparted angularly to the axis of the said switch, and thereby close the circuit of said switch. 100 105 110

9. A circuit closing mechanism including an inverted U-shaped member, an insulation block supported thereby, a dome shaped contacting member embedded in the latter, a flat spring interposed between the said U member and the said block, and anchored in a fixed position therein, an actuating member mounted in the said yoke having its lowermost portion extended slightly past the normal plane of the spring and being held firmly against the said yoke by the resiliency of the said spring to prevent rattle of said parts. 115 120 125

10. A circuit closing mechanism including a supporting yoke, an insulation block supported thereby, a dome shaped contacting member embedded in the latter, a flat spring interposed between the said yoke and the 130

said block, and anchored in the said yoke in a fixed position, an actuating member having its lowermost portion sufficiently extended through the said yoke, as to cause 5 a retractile engagement of the said spring therewith for a purpose of preventing a rattle between the said parts.

11. A circuit closing mechanism including an inverted U-shaped member, an insulation 10 block supported thereby, a dome shaped contacting member embedded in the latter, a flat spring interposed between the said U member and the said block, and anchored in a fixed position within the U member,

an actuating member having its lowermost 15 portion sufficiently extended through the said yoke, to cause a retractile engagement of the said spring therewith for a purpose of preventing a rattle between the said parts, the said actuating member being so 20 mounted in the said yoke as to assume temporarily a limited tilting position with respect to the said spring when pushes are imparted to the said member other than square and central along its axial line. 25

In testimony whereof I affix my signature.

LLOYD BLACKMORE.
